OZONE PRODUCING APPARATUS

Filed Sept. 19, 1935

UNITED STATES PATENT OFFICE

2,093,619

OZONE PRODUCING APPARATUS

Rae R. Powell, Maywood, Ill., assignor to The
Electroaire Corporation, Chicago, Ill., a cor-
poration of Illinois

Application September 19, 1935, Serial No. 41,228

1 Claim. (Cl. 204—32)

The present invention relates generally to apparatus for producing ozone. More particularly the invention relates to that type of apparatus which is adapted to produce ozone for air purifying and other purposes and comprises a plurality of horizontally extending, laterally spaced generating units each of which consists of (1) a dielectric in the form of a glass tube; (2) a negative electrode in the form of a cylindrically-shaped piece of sheet metal which is disposed within and extends longitudinally of the dielectric and engages the inner face of the latter; and (3) a positive electrode in the form of a pair of semi-cylindrical, sheet metal plates which have a plurality of instruck, V-shaped projections, are clamped around the dielectric and operate when electrical current or energy is supplied thereto to form ozone as the result of the brush discharge around the points of the projections.

One object of the invention is to provide an ozone apparatus of this type which is an improvement upon previously designed apparatus of the same general character by reason of the fact that it includes a clamping structure which serves to hold the generating units in laterally spaced relation and at the same time operates conjointly and releasably to hold around the dielectrics the semi-cylindrical, projection-equipped plates which constitute the positive electrodes of the units.

Another object of the invention is to provide an ozone apparatus of the last mentioned type and character in which the clamping structure consists of a pair of superposed frames which have semi-cylindrical, oppositely facing, complementary seats for the generating units and are clamped together by means of bolts which permit of an adjustment of the clamping pressure of the frames on the projection equipped plates of the positive electrodes and make it possible to bring the points of the projections into close contact with the outer or external surfaces of the dielectrics and thus reduce materially the amount of current which is necessary to produce a given or predetermined amount of ozone.

A further object of the invention is to provide an ozone producing apparatus which is generally of new and improved construction and permits of quick and ready dismantlement of the various parts of the generating units for cleaning purposes.

Other objects of the invention and the various advantages and characteristics of the present ozone apparatus will be apparent from a consideration of the following detailed description.

The invention consists in the several novel features which are hereinafter set forth and more particularly defined by the claim at the conclusion hereof.

In the drawing which accompanies and forms a part of this specification or disclosure and in which like numerals of reference denote corresponding parts throughout the several views:

Figure 1 is a plan view of an ozone producing apparatus embodying the invention; 10

Figure 2 is a side view showing in detail the manner in which the frames of the clamping structure serve releasably and conjointly to hold around the dielectrics the projection equipped plates which constitute the positive electrodes; 15

Figure 3 is a vertical transverse section taken on the line 3—3 of Figure 2 and exhibiting the manner in which the clamping structure serves to hold the generating units of the apparatus in laterally spaced relation; and 20

Figure 4 is a perspective of one of the frames of the clamping structure of the apparatus.

The apparatus which forms the subject matter of the invention is adapted to produce ozone for air purifying and other purposes and comprises a group of three generating units 5, 6 and 7, and a clamping structure 8 for holding the units horizontally and in laterally spaced or serially arranged relation. 25

The generating unit 5 consists of a dielectric 9, a negative electrode 10, and a positive electrode 11. The dielectric is in the form of a glass tube, one end of which is closed in order to prevent air from passing or flowing therethrough and depositing dust on the inner face thereof. The negative electrode 10 is in the form of a cylindrical piece of sheet metal and is disposed within, and extends longitudinally of, the dielectric. The piece of sheet metal which forms or constitutes the negative electrode fits against the inner face of the dielectric and is pressed or clamped outwardly by means of a split ring 12 and a coil 13 of wire. The split ring 12 is disposed adjacent to the closed end of the dielectric and the wire coil 13 is positioned near the open end of the dielectric and has an end piece 14 which projects from the dielectric and is connected to a grounded bus bar 15. The positive electrode 11 consists of a pair of semi-cylindrical sheet metal plates 16 and is supplied with current by way of a conductor 17. The plates 16 are held in clamped relation around the dielectric 9 by means of the clamping structure 8 and have instruck V-shaped projections 18. The latter are adapted to engage the outer or external face of the di-

- electric and are preferably arranged in rows which extend lengthwise of the plates. When current or electrical energy is supplied to the positive electrode there is a brush discharge around the points of the projections 18. This discharge operates to produce ozone from the air which is around or passes through the space between the dielectric and the plates 16 of the positive electrode.
- 5 The generating units 6 and 7 are the same in design and construction as the unit 6, and as shown in Figure 1 of the drawing, the end pieces of the wire coils for holding the negative electrodes in place are attached to the grounded bus bar 15.
- 10 The clamping structure 8 for holding the generating units horizontally and in laterally spaced or serially arranged relation is mounted on a supporting panel 19 and consists of an upper frame 20 and a lower frame 21.
- 15 The upper frame 20 overlies the generating units 5, 6 and 7 and comprises a pair of laterally spaced, metallic straps 22 and a pair of cross-bars 23. The straps 22 are shaped by a forming die or like instrumentality so that each embodies three substantially semicircular, seat-forming parts 24, 25 and 26 and a pair of flat connecting parts 27 and 28. The seat-forming parts 24 are located at one side of the frame 20 and extend 20 over the upper end portions of the positive electrode 11 of the generating unit 5. The seat-forming parts 26 are located at the other side of the frame 20 and encircle or extend over the upper end portions of the positive electrode of the generating unit 7. The substantially semicircular seat-forming parts 25 of the straps are disposed 25 between the parts 24 and 26. They are connected to said parts 24 and 26 by the flat connecting parts 27 and 28 and are adapted to extend over 30 the upper end portions of the positive electrode of the intermediate generating unit 6. As shown in the drawing, the seat-forming parts 24, 25 and 26 of the straps are substantially equal as far as radius is concerned to the projection-equipped 35 plates which constitute the outer or positive electrodes of the generating units. They are, however, less than 180° in circumference. The straps 22 are held in laterally spaced relation by means of the crossbars 23. One of these bars extends 40 between and is connected by rivets 29 to the flat connecting parts 27 of the straps and the other crossbar extends between and is connected by rivets 30 to the flat connecting parts 28. The bars 23 are formed of metal and serve as conductors or electrical connections between the two 45 straps 22.
- 50 The lower frame 21 is in the nature of a complement of the upper frame 20. It underlies the generating units 5, 6 and 7 and consists of a pair of laterally spaced, metallic straps 31 and a pair of metallic crossbars 32. The straps 31 are vertically aligned with the straps 22 of the frame 20 and are shaped by a forming die so that they embody three substantially semicircular seat-forming parts 33, 34 and 35, and a pair of flat connecting parts 36 and 37. The parts 33 are located beneath the substantially semicircular parts 24 of the straps 22 and extend under and around the lower end portions of the positive 55 electrode 11 of the generating unit 5. The seat-forming parts 35 of the straps 31 underlie the parts 26 of the straps 22 and extend under and around the lower end portions of the positive electrode of the generating unit 7. The seat-forming 60 parts 34 of the straps 31 are located between the

parts 33 and 35. They are connected to the latter by the flat connecting parts 36 and 37 and extend under and around the lower end portions of the positive electrode of the generating unit 6. The crossbars 32 serve to hold the straps 31 in laterally spaced relation and also as connectors for said straps. One of the bars extends between and is connected by rivets 38 to the connecting parts 36 of the straps 31. The other bar extends between and is connected by rivets 39 to the flat connecting parts 37 of the straps 31. The lower frame 21 is connected to the supporting panel 19 by means of four legs 40. These legs serve to space the clamping structure from the panel and are formed by bending downwards and then inwards the ends of the straps 31. Bolts 41 are carried by the panel 19 and extend through the inturned part of the legs so that they serve fixedly or rigidly to secure the lower frame 21 to the panel. As shown in Figure 3, the conductor 17 10 of the generating units is secured to one of the legs 40.

15 In addition to the upper frame 20 and the lower frame 21 the clamping structure comprises 20 a pair of bolts 42. These bolts are adapted to draw the two frames together and cause the straps of the frames to clamp the projection-equipped plates around the dielectrics of the generating units. As shown in Figure 3 of the drawing, the bolts 42 extend through the central portions of the crossbars of the two frames and are provided at their upper ends with nuts 43. By tightening these nuts it is possible so to urge together the frames that the projection-equipped 30 plates are all firmly or tightly clamped against the dielectrics of the generating units regardless of any irregularity in the diameter of the dielectrics due to commercial variation. The seat-forming parts 33, 34 and 35 of the straps 31 of the 35 lower frame correspond as far as radius is concerned to the positive electrodes and are less than 180° in circumference so that the connecting parts 36 and 37 are spaced from the connecting parts 27 and 28 respectively and it is thus possible 40 to exert any desired clamping pressure on the plates which constitute the positive electrodes. The clamping structure constitutes simple means for conjointly clamping the positive electrodes of the generating units against the dielectrics and the bolts 43 constitute simple means for adjustably drawing the frames of the clamping structure together in order to bring all of the V-shaped projections of the positive-electrode-forming plates into contact with the dielectrics. By providing means for bringing the points of all of the projections into contact with the dielectrics the apparatus as a whole is exceedingly efficient and requires but a minimum amount of current to produce a given or predetermined amount of ozone. When it is desired to dismantle the generating units for cleaning purposes it is only necessary to remove the nuts 43 from the bolts 42 and then remove the upper frame 20. By reason of the fact that the clamping structure includes 50 the two frames which in effect serve as a multiple clamping unit the generating units are spaced equidistantly apart and held in fixed relation.

55 Inasmuch as the ozone apparatus includes the improved clamping structure, it may be manufactured at a low and reasonable cost and is exceptionally efficient as far as ozone production is concerned.

60 Whereas the apparatus has been described as 75

comprising three generating units and the clamping structure has been described as being adapted for three generating units it is to be understood that the apparatus may comprise any number of generating units and that the clamping structure may be modified to accommodate and effect conjoint clamping of the positive electrodes of any desired number of units. It is also to be understood that the invention is not to be restricted to the details set forth, since these may be modified within the scope of the appended claim without departing from the spirit and scope of the invention.

Having thus described the invention, what I claim as new and desire to secure by Letters Patent is:

An ozone apparatus comprising in combination a series of side by side, equidistantly spaced ozone generating units each including a tubular dielectric and an electrode extending around the dielectric and consisting of complementally arranged arcuate metallic plates with instruck di-

electric-engaging projections throughout substantially the entire area thereof; a combined clamping and unit-retaining structure consisting of a pair of oppositely facing complementary frames each of which embodies a pair of laterally spaced metallic straps shaped to form substantially semicircular unit-receiving parts and flat connecting parts between said receiving parts, metallic crossbars extending between, and secured at the ends thereof to, the connecting parts of the straps and operative to hold the straps in laterally spaced relation, and bolts extending through the central portions of the crossbars and adapted to draw the two frames together in order conjointly to clamp the plate-formed electrodes of the units around their respective dielectrics and to bring the projections of the plates into firm contact with the outer faces of the dielectrics; and a conductor attached to one of the frames for supplying current to the units.

RAE R. POWELL.
